CLAIM

The ornamental design for a terminal portion of an insertable probe used for indicating fuel tank levels, as shown and described.

DESCRIPTION

FIG. 1 is a perspective view of terminal portion of an insertable probe used for indicating fuel tank levels, showing my new design;

FIG. 2 is a front elevational view thereof;

FIG. 3 is a rear elevational view thereof;

FIG. 4 is a top plan view thereof; and,

FIG. 5 is a side elevational view thereof.

FIG. 1

FIG. 4

FIG. 5

FIG. 2

FIG. 3
